UNITED STATES PATENT OFFICE

99,004

DESIGN FOR A JUVENILE AUTOMOBILE

Walter H. Diemer, Toledo, Ohio, assignor to The American-National Company, Toledo, Ohio, a corporation of Ohio

Application January 16, 1936, Serial No. 60,627

Term of patent 7 years

To all whom it may concern:

Be it known that I, Walter H. Diemer, a citizen of the United States and resident of Toledo, county of Lucas, State of Ohio, have invented a new, original, and ornamental Design for a Juvenile Automobile, of which the following is a specification, reference being had to the accompanying drawing, forming a part thereof.

In the drawing, Fig. 1 is a perspective view of a juvenile automobile embodying the invention, and Fig. 2 is a fragmentary rear end perspective view thereof.

The dominant feature of my design resides in the form of the rear portion of the body, which is prominently displayed by shading.

I claim:

The ornamental design for a juvenile automobile, substantially as shown and described.

In testimony whereof I have hereunto signed my name to this specification.

WALTER H. DIEMER.
